[57] CLAIM

The ornamental design for a shower stall soap dish, as shown and described.

DESCRIPTION

FIG. 1 is a top plan view of a shower stall soap dish, showing my new design;

FIG. 2 is a front elevational view thereof, the rear being unornamented;

FIG. 3 is a bottom plan view thereof;

FIG. 4 is a left end elevational view thereof, the right end being a mirror image;

FIG. 5 is a top plan view of a second embodiment of the design of FIG. 1;

FIG. 6 is a front elevational view of FIG. 5, the rear being unornamented;

FIG. 7 is a bottom plan view of FIG. 5;

FIG. 8 is a left end elevational view of FIG. 5, the right end being a mirror image;

FIG. 9 is a top plan view of a third embodiment of the design of FIG. 1, the only difference being a decrease in length;

FIG. 10 is a top plan view of a fourth embodiment of the design of FIG. 1, the difference being a further decrease in length;

FIG. 11 is a top plan view of a fifth embodiment of the design of FIG. 1;

FIG. 12 is a front elevational view of FIG. 11, the rear being unornamented;

FIG. 13 is a bottom plan view of FIG. 11;

FIG. 14 is a left end elevational view of FIG. 11, the right end being a mirror image.
